(57) **CLAIM**

The ornamental design for a fastening device as shown and described.

DESCRIPTION

1. Fastening Device

1.1 is a perspective view of a fastening device showing my new design;

1.2 is a front view thereof;

1.3 is a left side view thereof;

1.4 is a right side view thereof;

1.5 is a rear view thereof;

1.6 is a top view thereof; and

1.7 is a bottom view thereof.

The broken lines and areas within them depict portions of the fastening device that form no part of the claimed design.
